[57] **CLAIM**

The ornamental design for handle for a composting toilet, as shown and described.

DESCRIPTION

FIG. 1 is a front perspective view of a composting toilet drawn in dashed outline to show surrounding structure, the subject handle being shown in a stored orientation disposed in association with the toilet;

FIG. 2 is a similar view to FIG. 1 showing the handle in an operative orientation;

FIG. 3 (drawn to a larger scale) is a front perspective view of the handle in the operative orientation shown in FIG. 2;

FIG. 4 (drawn to a larger scale) is a rear perspective view of the handle in the operative orientation shown in FIG. 2; and,

Three (3) sheets of drawings showing the said Industrial Design are hereunto annexed.

FIG. 1

FIG. 2

FIG. 3

FIG. 4
